FUSE CLAMP

Carl M. Gura, Cleveland, Ohio, assignor of one-half to Ernest J. Elliott, Mentor, Ohio

Application November 30, 1935, Serial No. 52,373

6 Claims. (Cl. 200—134)

This invention relates to fuse clamps and has for its main object to provide a fuse clamp which will force in unison each pair of the arms of the fuse clips holding the ends of the fuse into engagement therewith to provide good contact between the clips at both ends of the fuse to prevent an arc at these points.

A further object of this invention is to provide a fuse clamp of the above character, which is simple in construction, is easily applied to both pairs of fuse clips, and in which both pairs of clamps are actuated by a single operating means.

With the above and other objects in view, the invention will be hereinafter fully described with reference to the accompanying drawing, and the novel features thereof will be distinctly pointed out in the appended claims.

In the several views of the drawing, similar parts are designated by the same reference characters, and although the clamp is illustrated for a ferrule type fuse, it will be understood that the invention is applicable for a knife-blade type fuse.

Figure 1 is a side view of an ordinary ferrule fuse with a clamp constructed in accordance with my invention applied thereto.

Fig. 2 is an end view of Fig. 1.

Fig. 3 is a plan view of the clamp.

Fig. 4 is an end view of the clamp, the actuating and locking bar being in its longitudinal position and the leaves in their up position.

Fig. 5 is a cross-sectional view, on an enlarged scale, through the adjusting bolt of the clamp or on line 5—5 of Fig. 3.

Fig. 6 illustrates the adjusting bolt fixed in the bar.

Fig. 7 is plan view of clamp with signal light.

Fig. 8 illustrates circuit from the light to hinged members, and

Fig. 9 the spring pressed contact pin of the circuit.

Referring to the drawing, 1 represents a base of suitable insulating material, to which is fixed at 2, two clips 3 and 4, each having a pair of spring arms 5 and 6 which are adapted to grip the capped ends 7 and 8 of the ordinary fuse 9 for electric circuits. It has been found in practice that for various reasons, the pairs of spring arms 5 and 6 do not make full, complete and proper contact with one or both of the ends of the fuse, and consequently there is loss of electrical energy and other undesirable results. In order to cause the spring arms of the clips to make good contact with both ends of the fuse and thus assure efficiency and avoid the difficulties resulting from

poor contact between the clips and the fuse, this fuse clamp has been designed.

The fuse clamp consists of a pair of plates or leaves 10 and 11 of fibre or other suitable insulating material, which leaves are pivotally connected together at 12 and 13 by means of pairs of hinged members 14 and 15, which are fixed as at 16 to the lower sides of said leaves. The pivotally connected leaves 10 and 11 are of sufficient length so that the pairs of hinged members 14 and 15 will be directly over the clips 3 and 4 when the clamp is applied thereto. The hinged members 14 and 15 have turned down or depending arms 17 and 18, which are adapted to fit over and engage the upper or free ends 19 and 20 of the spring arms 5 and 6 of the clamps 3 and 4 for forcing same into contact with the ends of the fuse.

For actuating the leaves 10 and 11 downwardly in unison to cause the depending arms 17 and 18 of the pairs of hinged members 14 and 15 to exert gripping pressure upon the clips 3 and 4, and also lock said leaves in their final down positions, the following described mechanism is employed.

One of the leaves as 10 is provided at its inner edge with a central lateral lug 21 and the other leaf 11 with a complementary recess 22 for accommodating same. On the pivotal line of the hinged members at 12 and 13 of the leaves 10 and 11, the lug 21 is provided with a central opening 23 for receiving a bolt 24 depending from a strip of metal 25 embedded in a bar 26 of suitable insulating material adapted to actuate and lock the leaves 10 and 11. The opening 23 of the leaf 10 is sufficiently large to permit up and down movement of said leaf, and a washer 27 is loosely mounted over the bolt 24 and slidably engages the under side of said leaf. An adjusting nut 28 on the bolt 24 is rounded at 29 for engaging the edges of the opening of the washer 27 for providing a ball and socket movement, and said adjusting nut is knurled at 30 for convenient manipulation. By rotating the bar 26 to an angular position, it slidably engages the upper surfaces of the leaves 10 and 11, thereby forcing same downwardly and then also locking them in a set position. When the bar 26 is in its longitudinal position relative to the pivotal center of the leaves 10 and 11, said leaves may be tilted upwardly from said pivotal center and the depending arms of the hinged members thereby spread apart for fitting over the ends of the arms of the spring clips. After applying the arms of the hinged members to the spring clips, the turning of the bar 26 on its pivotal bolt will cause it to slidably

engage the upper surfaces of the leaves 10 and 11 and force same downwardly thereby causing said arms of said hinged members to clamp said arms of the clips to said fuse.

5 When the clamp is in use and a fuse has blown, it is desirable to have a signal light show. For this purpose, a neon light 31 is arranged in the bar 26, and wires 32 and 33 lead therefrom to spring pressed contact pins 34 and 35, which are 10 adapted to enter shallow depressions indicated by 36 of the leaves 10 and 11. From the depressions 36 extend wires as at 37 leading to the hinged members at 12 and 13. In event a fuse blows, the circuit is closed by the current passing from one clip to the other by way of the hinged members at 12 and 13 the wires 31, the contact pins 34 and 35, the wires 32 and 33 and neon light 31, thereby showing a signal.

From the drawing and description, it is thought 20 that the construction and operation and advantages of this double clamp for fuses will be appreciated by those skilled in the art, and it will be understood that changes in the details of construction may be made for carrying out the invention and within the claims.

Having fully described my invention, what I claim is:

1. In a fuse clamp, the combination of a pair of hinged members, the hinged members having 30 arms adapted to engage the arms of spring clips, the hinged members being normally tilted upwardly from and above the pivot point, and means for actuating the hinged members downwardly to cause said arms thereof to force the arms of the spring clips in contact with a fuse.

2. In a fuse clamp, the combination of a pair of hinged members, the hinged members having arms adapted to engage the arms of spring clips, the hinged members being normally tilted upwardly from the pivot point, and a bar adapted to slidably engage said hinged members for actuating same downwardly.

3. In a fuse clamp, the combination of a pair of leaves, hinged members, the leaves being fixed 45 to said hinged members, the hinged members

having arms adapted to engage the arms of spring clips, the leaves being normally tilted upwardly, and means adapted to actuate said leaves downwardly to cause said arms of said hinged members to force the arms of pairs of spring clips 5 in contact with a fuse.

4. In a fuse clamp, the combination of a pair of leaves, hinged members, the hinged members being fixed to said leaves, the hinged members having arms adapted to engage the arms of spring 10 clips, the leaves being normally tilted upwardly, a bar, the bar being pivotally supported by one leaf, and the bar being adapted to slidably engage said leaves when rotated to actuate same downwardly to cause said arms of said hinged 15 members to force the arms of both pairs of clips in contact with the ends of the fuse.

5. In a fuse clamp, the combination of a pair of leaves, hinged members, the hinged members being fixed to said leaves, the hinged members 20 having arms adapted to engage the arms of spring clips, the leaves being normally tilted upwardly, a bar, the bar being pivotally supported by one of said leaves, the bar being adapted to slidably engage said leaves upon rotation of the bar to 25 actuate said leaves downwardly to cause said arms of said hinged members to force the arms of pairs of clips in contact with the fuse, and means for adjusting the position of said bar relative to said leaves.

6. In a fuse clamp, the combination of a pair of leaves, hinged members, the hinged members connecting said leaves, the hinged members having arms adapted to engage the arms of spring 30 clips, the leaves being normally tilted upwardly, 35 a bar, a pivot bolt, the bolt being supported by one of said leaves, the bar being on said bolt, the bar being adapted to slidably engage said leaves upon rotation to force same downwardly to cause the arms of said hinged members to 40 force the arms of the spring clips to grip said fuse, and a nut upon said bolt adapted to adjust said bar relative to said leaves.

CARL M. GURA. 45
